HAIR CURLING DEVICE

Rocco Pezzella, Washington, D. C.

Application March 30, 1932. Serial No. 602,054

10 Claims. (Cl. 132—33)

In the curling of hair on the human head it is the custom to take individual locks, wind them around a mandrel or rod, and while so wound, subject the same to a steam treatment. The winding operation in order to secure genuinely beautiful effects requires much care and experience, and up to the present time has been most successfully accomplished by wrapping the hair by hand. Numerous devices have been proposed 10 for mechanically winding the locks of hair on the mandrel, but experience has demonstrated that these do not nicely place the lock in flattened condition as it should be, nor effectively hold the lock after it has been wound. A careful 15 study of the hand operation by an expert shows certain successive actions by the thumbs and fingers of the operator in winding and properly laying the hair on the mandrel.

One of the objects of the present invention 20 is to provide a mechanical winding device for the purpose that will simulate to a marked degree the operations of the human fingers and thumbs, and actually improve on such action by being constantly in engagement with the lock 25 of hair during the winding operation, as distinguished from the human fingers which must move from place to place and thus at intervals be free from the hair that is being wound.

In applying a lock of hair to a mandrel or rod 30 the convolutions should be placed counter-clockwise in order to obtain the best effects. There are two generally recognized forms of wrapping or winding. The first is a flat spiral wind ordinarily used on very fine and thin hair and produces what is known as the ringlet curl. In winding the hair for this style the convolutions run side by side or very slightly overlap, so that they extend a considerable distance along the mandrel or rod. The second is known as 35 "croquignole". It is ordinarily used on coarser hair, which takes curl more readily than finer hair and makes a larger wave. It consists in placing the convolutions almost completely one over the other until the entire lock is wound.

40 A further and important object of the present invention is to provide a device which will wind the locks of hair in either manner.

Still another object is to provide a structure which may be left on the rod after a lock has 50 been wound thereon and will act as an effective securing means to hold the wound lock in place during treatment.

The preferred embodiment of the invention is 55 illustrated in the accompanying drawings, wherein

Figure 1 is a perspective view showing the winder in place on a rod or mandrel and indicating the parts that correspond to the fingers and thumbs of the human hand during a winding operation.

Figure 2 is a side elevation of the winding device on the mandrel.

Figure 3 is also a view in elevation on a different side from that shown in Figure 2, and illustrating a lock of hair at the beginning of the 65 wrapping operation.

Figure 4 is a perspective view showing the device at substantially the completion of a flat spiral wind.

Figure 4a is a side elevation but illustrating the 70 device when a "croquignole" wind is made.

Figure 5 is an end elevation of the winding device.

Figure 6 is a longitudinal sectional view taken 75 on the line 6—6 of Figure 5.

Figure 7 is a sectional view on the line 7—7 of Figure 4a.

Figure 8 is a longitudinal sectional view taken 80 on the line 8—8 of Figure 5.

The device as shown consists of a body 9, preferably of aluminum or other suitable material, and having a longitudinal bore 10 adapted to receive a mandrel or rod 11 on which the device is rotatable.

In one end of this device is an internal throat 85 12 that opens through said end and tapers rearwardly therefrom so that it will have an unshouldered junction 13 with the bore 10. One side of the end portion of the body having the throat 12 is cut away to produce a mouth 14

90 that opens into the throat 12 and also opens through the same end of the body, through which said throat 12 opens. This mouth, as will be evident by reference particularly to Figures 2 and 4, has a wide freely open end at the end of the 95 body. One of the side walls 15 of the mouth has an internal rounded thickened portion 16 which corresponds somewhat to the form of the ball of a human finger. The opposite side wall 17 has a corresponding internal thickened portion 18.

Projecting into the mouth 14 from its inner end and towards its outer open end, is a tongue piece 19 which tapers towards its free end, as will be clear by reference to Figure 2. In order to lighten the body it is preferably cut 105 away at various points as shown at 20, producing openings or slots. In order that the device may be placed close to the scalp and thus permit the hair to be wound at a point beginning close to the head, the end of the body on the side directly 110

opposite the open end of the mouth is recessed or notched as shown at 20a. For the purpose of tensioning the lock of hair, while it is being wound, a pair of clamping jaws are provided. 5 One of these is designated 21 and is preferably hingedly mounted as shown at 22 on the body. The jaw may carry a friction piece 23 that will bear upon the lock of hair as shown in Figure 4. This structure may be on the order of the clamp- 10 ing device disclosed in my co-pending application, Serial No. 529,176. The other jaw is designated 24 and is of the same general structure. As will be noted, by a comparison of Figures 4 and 4a the two jaws 21 and 24 are differently disposed 15 on the body, the jaw 21 being located diagonally in rear of the mouth 14, and the jaw 24 being located longitudinally of the body and at one side of the mouth.

Considering Figure 1 wherein is shown not only the winding device, but human hands, the position of the hands is substantially that of an expert in winding the hair by hand and without the device. It will be noted that the thumb A of the left hand is pressing upon the convolution that has been 20 completed, while the index finger B will press upon the lock of hair just at the point where the next convolution is being formed. The thumb C and the index finger D of the right hand are not only holding the free portion of the lock of hair and applying it to the mandrel or rod, but the thumb C is also flattening the lock and pressing it on the rod. As the hair is wound it will be evident that the thumbs and fingers must be moved from point to point, it being understood 25 of course that at least one thumb or finger is always in position to prevent any tendency of the lock to unwind. If now the parts of the mechanical device herein disclosed are considered in connection with the positions of the fingers, it will be noted that the wall 15 of the mouth and 30 the thickened portion 16 act precisely the same as the finger B of the left hand in that these portions are pressing on the lock at the point of its application to the mandrel. In like manner the thickened or balled portion 18 of the opposite wall 17 of the mouth is pressing on the 35 underlying convolution that has been previously made and is acting in the same manner as the thumb A of the left hand. The tongue 19 is at the same time taking the place of the thumb C in that it is flattening the lock just prior to its 40 application to the mandrel or rod, while one of the clamping devices 21 or 24 (see Figures 4 and 4a) is acting in the capacity of the combined 45 thumb C and finger D, in not only laying the lock in flattened condition, but putting frictional resistance thereon so that a properly tightened winding operation is assured. Obviously as these 50 parts are always in action on the lock, they are continuously performing their respective functions as against the fingers which must move from place to place and individually be disengaged at times from the hair.

As will be clear by a comparison of Figures 4 55 and 4a, when a spiral wind for the production of ringlet curls is desired, the lock of hair is passed through the friction device 21 and as the device is rotated counter-clockwise on the rod or mandrel 11 a long spiral wind will be obtained. If a "croquignole" wind is desired, then the hair is passed through the other longitudinally disposed friction device 24. The enlarged mouth in such a case permits the formation of convolutions directly or substantially directly one over the other, after which the device will shift slightly and more

such convolutions will be made until the entire lock of hair is wound.

The winder is thus adapted for use in the production of either form of winding operation. When a lock has been completely wound, it is only necessary to give one or two extra turns to the winder and crowd it slightly toward the wrapped hair, whereupon because of the unshouldered juncture between the tapered throat and the bore 10 the device will effectively clamp itself and thus hold the hair during the steam or other treatment. This clamping action is furthermore assisted by the balled portions 16 and 18, which as has been noted, do not however constitute a sharp shoulder against the clamping operation.

From the foregoing, it is thought that the construction, operation and many advantages of the herein described invention will be apparent to those skilled in the art without further description, and it will be understood that various changes in the size, shape, proportion and minor details of construction may be resorted to without departing from the spirit or sacrificing any of the advantages of the invention.

What I claim, is:

1. A hair winding device for rotatable mounting on a mandrel and having a hair receiving mouth provided with opposite side walls each having an internal balled portion, said balled portions cooperatively pressing on the lock of hair as it is wound on the mandrel by the rotation of the device in one direction.

2. A hair winding device for rotatable mounting on a mandrel and having a hair receiving mouth provided with opposite side walls, each of said walls having an internal balled portion, said balled portions cooperatively pressing on the lock of hair as it is wound on the mandrel by the rotation of the device in one direction.

3. A hair winding device for rotatable mounting on a mandrel and having a hair receiving mouth provided with an outer receiving end and a tongue projecting into the same from its inner end portion toward said outer end.

4. A hair winding device for rotatable mounting on a mandrel and having a hair receiving mouth having an open outer end provided with opposite side walls both having means for guiding and shaping the lock of hair as it is wound on the mandrel, and a tongue projecting into the mouth from its inner end portion and extending toward said outer end.

5. A hair winding device for rotatable mounting on a mandrel and having a hair receiving mouth provided with opposite side walls, each of said walls having an internal balled portion for pressing on the lock of hair as it is wound on the mandrel, said mouth having a substantially tapered tongue projecting from its inner end portion toward its outer open end.

6. A hair winding device for rotatable mounting on a mandrel and having a longitudinally disposed mouth having a wide outer open end that opens through the end of the device and having unlap spaced opposite side walls adapted to bear respectively upon successive wraps of hair.

7. A hair winding device for rotatable mounting on a mandrel and comprising a rotatable body having a bore therethrough for receiving a mandrel, said body having an enlarged open ended internal throat at one end and a longitudinally disposed mouth that opens through a side wall and one end, the opposite walls of the mouth being unlap spaced apart and 150

operating to press upon the hair wrapped on the mandrel by said device.

8. A hair winding device for rotatable mounting on a mandrel and comprising a rotatable body having a bore therethrough for receiving a mandrel, said body having an enlarged inwardly tapered internal throat that has an unshouldered juncture with the bore, and a mouth that opens through a side wall and one end, the 10 opposite walls of the mouth operating to press upon the hair wrapped on the mandrel by said device.

9. A hair winding device for rotatable mounting on a mandrel and having a hair receiving mouth provided with opposite side walls, both 15 having means for guiding and shaping the lock of hair as it is wound on the mandrel, and means

on the device for placing tension on the hair as the device is rotated.

10. A hair winding device for rotatable mounting on a mandrel and comprising a rotatable body having a bore therethrough for receiving a mandrel, said body having an enlarged inwardly tapered internal throat that has an unshouldered juncture with the bore, a mouth that opens through a side wall and one end, the opposite walls of the mouth operating to press upon the hair wrapped on the mandrel by said device, a generally tapered hair pressing tongue extending into the mouth towards its open end, and means on the body placing tension on the hair as the body is rotated.
